UNITED STATES PATENT OFFICE.

MORTIMER G. MERRITT AND FRANKLIN L. GROFF, OF ROME, NEW YORK,
ASSIGNORS TO THE ROME METALLIC BEDSTEAD COMPANY, OF SAME
PLACE.

CASTER.

SPECIFICATION forming part of Letters Patent No. 606,354, dated June 28, 1898.

Application filed December 8, 1896. Serial No. 614,963. (No model.)

To all whom it may concern:

Be it known that we, MORTIMER G. MERRITT and FRANKLIN L. GROFF, of Rome, in the county of Oneida and State of New York, have invented certain new and useful Improvements in Casters; and we do hereby declare that the following is a full, clear, and exact description of the invention, which will enable others skilled in the art to which it appertains to make and use the same, reference being had to the accompanying drawings, and to the figures of reference marked thereon, which form part of this specification.

This invention relates to casters particularly adapted for iron bedsteads, although equally applicable to use where casters are employed.

In the drawings, Figure 1 shows the lower end of a leg or post with our caster applied. Fig. 2 shows the same in vertical section. Fig. 3 shows the caster-securing pin or pintle in connection with its securing-spring and a washer. Fig. 4 shows a top view of the pin or pintle and the spring. Fig. 5 shows the same pintle and spring from a face view on the spring with the washer shown in section. Fig. 6 shows a perspective view of the washer. Fig. 7 shows a perspective view of the spring. Fig. 8 shows a perspective view of the caster removed from the post or leg.

Referring to the reference-figures in a more particular description, 1 indicates the post or leg, which in the construction as shown is provided with a foot or base 2. Into the lower end of the foot or leg is formed a pintle-hole or caster-socket 3, with an enlargement or chamber 4 at its upper end. The wheel or roller 5 of the caster is carried by arms 6, integral with the tubular body or sleeve 7. The pintle-pin 8 is provided with a head on its lower end and passes through the tubular body 7, and is adapted to enter the opening 3 in the lower end of the leg. The pin is secured in position in the body or sleeve 7 of the caster by the washer 9 wedging or binding on the pin or otherwise suitably secured. The washer 7 also secures the spring 10 by binding it against the flattened side of the

pin 8. The washer has a slight recess 8^a, adapted to receive the angled lower end of 50 the spring 10. The flattened side of the pin on which the lower end of the spring rests is at an angle with the body of the pin, and the point 8^b, where the flattening runs out, forms a fulcrum over which the spring bends. The 55 spring 10 is provided with a shoulder 10^a, adjacent to the upper end, and an inclined or beveled projection 10^b above the shoulder. The spring 10 is so held by the washer 9 that normally it will stand at an angle with the 60 pin 8.

In placing the caster in the leg the end of the pin 8 and the point of the inclined projection 10^b of the spring will enter the opening 3, which is flared slightly at the lower 65 end, and as the caster is forced into position the spring 10 is forced toward the pin sufficiently to allow the caster to come into proper position on the leg. When the caster has come to its proper position, the shoulder 70 10^a on the spring 10 catches on the shoulder 4^a at the upper end of the opening 3 in the lower end of the leg, and the caster is thereby secured in position, so that it will not drop out when the leg or piece of furniture to 75 which it may be attached is raised from the floor. The caster at the same time is free to rotate, preferably on the lower end of the pin 8, but if need be the whole pin, with the spring 10, will rotate in the lower end of the 80 leg. The shoulder 10^a on the spring being at somewhat of an obtuse angle with the body of the spring, the caster can be removed by forcibly drawing it out, the spring being forced back against the pin. To permit this 85 being done, it will be observed that the upper end of the pin is somewhat cut away, so as not to interfere with the projection 10^b in the operation of the spring.

What we claim as new, and desire to secure 90 by Letters Patent, is—

1. The combination with a caster of the pintle 8, the spring 10 secured to the side of the pintle and diverging therefrom, the washer 9 secured on the pintle and securing the spring 95 10 substantially as set forth.

2. The combination with a leg having a
caster-socket 3 with a shoulder 4° at its upper
end, of a caster having a pintle 8 and a di-
vergent spring 10 both adapted to enter the
5 socket, the washer 9 secured to the pintle and
securing the spring to the side of the pintle,
substantially as set forth.

In witness whereof we have affixed our sig-
nature in presence of two witnesses.

MORTIMER G. MERRITT.
FRANKLIN L. GROFF.
